UNITED STATES PATENT OFFICE.

OTIS ALLEN KENYON, OF NEW YORK, N. Y.

ELECTRIC WELDING.

1,229,288.

Specification of Letters Patent. Patented June 12, 1917.

Application filed March 3, 1917. Serial No. 152,315.

To all whom it may concern:

Be it known that I, OTIS A. KENYON, a citizen of the United States, residing at New York city, in the county of New York and State of New York, have invented certain new and useful Improvements in Electric Welding, of which the following is a specification.

My invention relates to electric welding and has for its essential object to increase the energy efficiency of electric arc welding.

As preliminary to a detailed description of the present invention, I would say that arc welding practice has been developed with constant-potential sources of electric energy, and regulation of the current has been obtained by resistance in series with the arc, the voltage being limited by the machine. Introduction of constant-current for welding has offered even less regulation of the arc than the constant-potential, until the invention of the closed-circuit system described in my former Patent No. 1,181,227, dated May 2, 1916, and in which system there was introduced the limitation of arc length by voltage and the elimination of excessive energy discharges caused by breaking arcs, by eliminating the breaking of the arc.

However, the constant-current closed-circuit system, although having perfect control of the heat in the arc due to automatic current-regulation and automatic voltage limitation and elimination of the breaking of the arc, is not a complete solution of the problem, above mentioned, because it cannot be used in certain lines of work, where the different objects to be welded are connected to a common ground. Under these conditions, a multiple connection of arcs must be used.

The present invention relates primarily to the application of the same principle of control that I have devised for constant-current closed-circuit systems, to constant-potential systems, namely, the controlling of the length of the arc by a voltage limitation, adjustable and independent of the voltage of the generator, and extinguishing of the arc without breaking.

In constant-current closed-circuit systems, the extinguishing of the arc by short-circuiting is the only way it can be done and maintain a closed circuit. In constant-potential

circuits extinguishing the arc by short-circuiting, increases the load of the generator; while in constant-current circuits, the extinguishing of the arc decreases the load of the generator. Therefore, in constant-potential circuits, I have resorted to a momentary short-circuiting of the arc which is just sufficient to kill said arc, and then I break the circuit at another point after the arc has been extinguished so that there is no inductive discharge into the weld.

With the above and other objects in view my present invention consists of the arrangements, and combinations of parts which I will hereinafter describe and claim, reference being had to the accompanying drawing wherein—

Figure 1 illustrates somewhat diagrammatically a system of electric welding embodying my invention.

Fig. 2 is a similar system somewhat modified.

Referring to Fig. 1, A and B are constant-potential mains connected across the terminals of a constant-potential generator. We will assume the arc-circuit to be from 1 through a ballast resistor, 2, and the arc 3 back to the line at 5. Connected across the terminals of the arc is a shunt wound contactor, 6, and in series with the arc is a contactor, 4, which contactor may be of any well known and desired type. 7 and 8 indicate appropriate circuit-closers having stems, the stem of the circuit-closer, 7, being controlled by coils 6 and 9 and the stem of the circuit closer 8 being controlled by the coil, 4. 10 is a closing switch the operation of which I will presently describe.

In operation and referring particularly to the system shown in Fig. 1, and the before described arrangement of the same, before striking an arc at 3, line-potential exists at the arc. Striking an arc at 3 closes the circuit at 8 and places the arc voltage across the coil 6. As soon as the voltage exceeds a predetermined limit, current through the coil 6, closes the circuit at 7, short-circuiting the arc and also the coil, 4. The short-circuit at 7 extinguishes the arc and drops the connection at 8, thus leaving the coil 6 out of the circuit until the arc is again started.

The coil 9 is connected on the same contactor as the coil 6, so that the circuit or

connection at 7 can be closed at any time by the closing switch 10, which may be located on the welding tool.

In practice, the welder would strike an arc and continue to operate it until he either draws too long an arc or wishes to stop deliberately. In case he draws too long an arc, the coil 6, short-circuits his arc; in case he wishes to stop deliberately he closes the switch, 10, whereupon the coil 9 short-circuits the arc producing a rise in voltage.

The system illustrated in Fig. 2 is similar to the one before described, except that it contains a slightly different form of controller which accomplishes everything which I have heretofore set forth and in addition thereto leaves the arc terminals dead, until the welder desires to begin the welding operation. In said Fig. 2, the arc circuit 1', 20 2', 3' and 5' is connected across the constant-potential mains, A', B'; in shunt with the arc is a contactor coil 6', and in series with the arc is a circuit-closing device or contactor 8', controlled by coil, 4', which is in 25 series with the short-circuiting contactor 7'.

In operating the system of Fig. 2, the terminals of the arc, 3', are dead until a coil, 14, which holds the contactor or circuit-closer 8', open, is short-circuited, by operating a switch, 15, which closes the contactor, 8', connecting the arc in the welding circuit. If the arc terminals are not in contact when this occurs full voltage will be impressed across the coil, 6', which will close the contactor, 7', and open the contactor, 8', the contactor, 7', falling out as soon as the contactor 8' is opened. Therefore, in order to start the arc, the operator must close the arc, 3', then close the switch, 15, which in turn 35 closes the contactor, 8', and then as the arc is drawn, the welding will continue until the predetermined length of the arc is exceeded, when the current through the coil 6', will short circuit the arc and then open the circuit at 8'.

In case the welder wishes to stop deliberately, the closing of the switch, 10', will through the coil, 9', accomplish the desired result.

Having thus described my invention what I claim as new and desire to secure by Letters Patent is:—

1. In electric welding, a welding arc cir-

cuit and electro-responsive means for opening the arc circuit at a point external to the arc at a predetermined arc voltage.

2. In electric welding, a welding arc circuit, and electro-responsive means for shunting the current around the arc before breaking the arc circuit.

3. In electric welding, a welding arc circuit, and electro-responsive means for shunting the current around the arc at a predetermined arc voltage before breaking the arc circuit.

4. In electric welding, a welding arc circuit, and electro-responsive means for shunting the current around the arc at a predetermined arc voltage before breaking the arc, and then opening the arc circuit.

5. In electric welding, a welding arc circuit, electro-responsive means for opening the arc circuit at a point external to the arc at a predetermined arc voltage, and means under the control of the welder to stop the arc at will.

6. In electric welding, a welding arc connected in a constant potential circuit, and means controlled by the voltage across the arc to shunt the current around the arc at a predetermined voltage.

7. In electric welding, a welding arc connected in a constant potential circuit, electro-responsive means adapted to momentarily short circuit the arc at a predetermined arc voltage and then open the arc circuit.

8. In electric welding, a welding arc connected in a constant potential circuit, and electro-responsive means for stopping the arc without raising the voltage at the arc.

9. In electric welding, a welding arc circuit adapted to be closed at the arc before current is passed therethrough, and means for opening the arc circuit at a point external to the arc at a predetermined arc voltage.

10. In electric welding, a welding arc circuit adapted to be closed at the arc before current is passed therethrough, means for opening the arc circuit at a point external to the arc at a predetermined arc voltage, and means under control of the welder to stop the arc at will.

In testimony whereof I affix my signature.

OTIS ALLEN KENYON.
